Olympus Kogaku Kogyo Kabushiki-Kaisha, Tokyo,
Japan

Filed Apr. 20, 1964, Ser. No. 79,587

Term of patent 14 years

(Cl. D26—14)

FIG. 1

FIG. 2

FIG. 3

FIG. 4

FIG. 5

FIG. 1 is a top plan view of a portable tape-recorder embodying the new design;

FIG. 2 is an elevational view of the front thereof;

FIG. 3 is an elevational view of the rear thereof;

FIG. 4 is an elevational view of the left side thereof; and

FIG. 5 is an elevational view of the right side thereof.

The dominant features of the design reside in the portions shown in full lines. The drawing figures are stippled to indicate contrast in appearance of surface portions of the portable tape-recorder.

I claim:

The ornamental design for a portable tape-recorder, substantially as shown and described.
